[57] CLAIM

[21] Appl. No.: 49,075

The ornamental design for a safety weather cap for a rotary
box type cartridge magazine, as shown and described.

[22] Filed: Jan. 16, 1996

DESCRIPTION

[51] LOC (6) Cl. 22-01

FIG. 1 is a perspective view of the front side, the right side
and the top end of a safety weather cap for a rotary box type
cartridge magazine showing my new design;
FIG. 2 is an elevational view of the left side thereof;
FIG. 3 is an elevational view of the right side thereof;
FIG. 4 is an elevational view of the front end thereof;
FIG. 5 is an elevational view of the back end thereof; and,
FIG. 6 is a plan view of the top end thereof.
The bottom of the safety weather cap for a rotary box type
cartridge magazine is not part of the claimed design.
